UNITED STATES PATENT OFFICE.

ARTHUR J. EVERE, OF CHICAGO, ILLINOIS, ASSIGNOR TO EVERE PAPER BOX CO., OF CHICAGO, ILLINOIS, A CORPORATION OF ILLINOIS.

PASTEBOARD-BOX-MAKING MACHINE.

1,257,988.

Specification of Letters Patent.

Patented Mar. 5, 1918.

Application filed July 19, 1917. Serial No. 181,513.

To all whom it may concern:

Be it known that I, ARTHUR J. EVERE, a citizen of the United States, residing at Chicago, in the county of Cook and State of Illinois, have invented certain new and useful Improvements in Pasteboard-Box-Making Machines, of which the following is a specification.

My invention pertains to machines for making boxes of the pasteboard, cardboard, or similar type, such for example, as are frequently used for the accommodation of garments, suits of clothes, etc., but it is, nevertheless, to be understood that the invention is not limited or restricted to the style, size, or shape of the box, or the purpose for which it may be employed.

One of the leading objects of the invention is the provision of a simple machine of this general character which will be economical to construct, which will so fold the blanks and form the corner portions that a box of considerable strength will be produced, with strong corners able to withstand all ordinary usages without breaking or tearing apart. The type of box produced also readily yields itself to shipment in flat condition if desired.

A further feature of the invention resides in the shape of blank which the machine handles, the blank being such that there is but little, that is, practically no waste, the material being employed advantageously for stiffening and strengthening the corners of the box.

Preferably, the overlapped corner flaps and tabs of the box are adhered together by glue, paste, or the like, whereby to obtain a joint of adequate area unlikely to become separated, the parts being secured together in the formation of the box.

Various other features of novelty and advantage will become apparent to those skilled in this art from a consideration of a preferred embodiment of the invention described in detail below and illustrated in the accompanying drawings, throughout the various views of which like reference characters refer to the same parts.

50 In the drawings:

Figure 1 is an elevation of one corner portion of the device;

Fig. 2 is a vertical section on line 2—2 of Fig. 1;

Fig. 3 is a similar section on line 3—3 of 55 Fig. 1;

Fig. 4 is a vertical section on line 4—4 of Fig. 2;

Fig. 5 is a horizontal section on line 5—5 of Fig. 4;

Fig. 6 is an enlarged view of the portion of the mechanism shown in the central part of Fig. 4, illustrating the elements of the structure more clearly by reason of their greater size and scale;

Fig. 7 is a horizontal section through the lower portion of the form;

Fig. 8 is a view more or less diagrammatic of the means adjustably connecting and associating together the four corner portions 70 of the structure set forth;

Fig. 9 is a fragmentary face view of one of the presses, and

Figs. 10 to 14 inclusive show perspectively the steps of folding up one corner portion 75 of a pasteboard blank.

The four corner portions of the machine are substantially alike, so that a description of the construction and operation of one will suffice for all, it being understood initially that the appliance has four forms or blocks one at each corner, around which the corresponding parts of the box are made simultaneously from a flat pasteboard or similar blank, and that these forms and 85 their associated folding and pressing mechanisms are readily adjustable toward and from one another, whereby boxes of different sizes may be readily produced.

This single corner portion of the appliance comprises a frame 20 on which is bolted a casting comprising a base-plate 21, parallel upright-walls 22, 23, and a connecting-wall 24. At the junction of walls 22 and 24 and integral therewith, is a depending form 95 or block 25 substantially square in cross-section, and it is around this that one corner of the box is to be made by means of suitable folding and pressing elements. The relation of the four forms 25, 25^a, 25^b, 25^c, to 100 one another is shown in a general way and diagrammatically in Fig. 8.

The pasteboard blank 26 of substantially, but not exactly, rectangular shape, is fed beneath these four forms by any approved 105 means, not shown, and its four corner portions are acted upon at the same time. Such flat blank, a corner section only of which is

indicated in Fig. 10, comprises a central rectangular part 27 of a size to constitute the box bottom or head, depending upon whether a box body or box cover is being made, surrounded by side and end flaps 28 and 29 adapted to be folded up to form on lines 30 and 31 respectively to constitute the side and end walls of the box. At each corner this blank is notched at 32 removing a small, substantially-square, waste piece, and it is slit diagonally at 33, separating the adjoining tabs 34 and 35 integral with the side and end flaps 28 and 29 and adapted to be bent up on lines 36 and 37 respectively. Before being bent to form the corner, the top surface of tab 35 and an adjoining area of the end flap 29 corresponding in size and shape to the companion tab 34 is coated with glue or other adhesive to hold the parts together and cause them to adhere when bent into shape.

When the flat blank is beneath the four forms, the outer edges of the latter are in register with the lines 30 and 31, the flaps 28 and 29 extending beyond the forms for folding up against their outer faces.

It is, of course, desirable to hold the blank up against the bottom face of the form during the folding operation, and to perform this function, I provide a bent arm 38 of the peculiar shape shown in the various figures, and fulcrumed at 39, the arm having a free, elevated, flat end 40 adapted to coöperate with the under face of the form, the arm 35 being otherwise bent to escape conflict with other portions of the machine. Such holding arm or finger is operated by means of a link 41 pivoted thereto at 42 and to a projection 43 extended from a lever 44 fulcrumed at 45 on another lever 46 adapted to oscillate on a fixed fulcrum 47. The lower end of lever 44 is bifurcated at 48 to straddle shaft 49, the latter being provided with an oscillatory, rectangular, guide block 50, arm 44 having as an actuating means a roller 51 traveling in a cam groove 52 cut in the face of a gear 53 mounted on the shaft as shown. Obviously, from an understanding of this construction, it will be apparent that this cam, through the connections shown, operates the bent arm 38 and the lever 46 actuating a reciprocating gripping or discharge mechanism hereinafter described.

Assuming that the blank is beneath the form and its corner portion held against its under surface by the end 40 of the arm 38, the folding operation will take place substantially as follows, and by the mechanism indicated.

It is first necessary to fold or bend up the tab 34 along line 36 and this is brought about by means of a bent ear or folder 54 (Figs. 4, 6, and 7), rockingly mounted to turn in the bearings 55 and 56. This folder

54 is of the peculiar configuration shown in Fig. 7, and has rigid therewith a pinion 57, the teeth of which are in mesh with those of a short rack 58 mounted on the end of a curved arm 59 fulcrumed at 60 and provided about midway of its length with an extension 61 (Fig. 4), carrying a roller 62 accommodated in a cam groove 63 of a cam 64 (Fig. 2) on a shaft 65 driven from the companion shaft 49 by means of intermeshing bevel gears 66 and 67, the shaft 65 being mounted to rotate in suitable bearings 68, 69, as shown in Fig. 2.

By a relatively-quick movement the folder 54 bends the tab 34 along the line 36 through an angle of approximately 180°, that is, over on to the flap 28, and then recedes, permitting such tab to spring back more or less to substantially the position shown in Fig. 11.

The next step in the operation is to simultaneously bend up the side flap 28 on the line 30 and the tab 35 on the line 37, these two lines being in register and the two parts 28 and 35 before bending being in the same horizontal plane. This folding is accomplished by means of a bender comprising two parts 70 and 71 separated more or less by a gap or recess bounded by the edges 72, 73, 74, and 75, (Fig. 7), which space in the unoperated position of the bender accommodates the folder 54 in a portion of its operating and supporting mechanism, the same recess being also employed to permit the pressing mechanism described hereinafter to coöperate with the blank and form. Bender 70, 71, constitutes a flat plate pivoted or hinged at 76, 77, adjacent to the form 25, but below it.

This double folder 70, 71, is connected by means of a link 78 below it to one substantially-horizontal arm 79 of a bell-crank fulcrumed at 80 and having a depending arm 81 equipped with a roller 82 received in a cam-groove 83 of the drive gear 53.

At about the same time that the side flap 28 and the tab 35 begin to swing upwardly, the end flap 29 is also folded upwardly and the tab 35 by engaging the previously folded tab 34 is guided as shown in Figs. 12 and 13 to the outside of the flap 28 as illustrated in Fig. 14, the end flap 29 coming up thus against the face of the form and the outer face of the tab 34. Such bending or folding of the end flap 29 and its associated tab 35 is accomplished by means of a folder 84 of the peculiar tapered formation shown in Fig. 7 and hinged or fulcrumed at 85, 85. It is operated from beneath by a link 86 pivoted to a projection on its under face and also pivoted to one arm 87 of a bell-crank fulcrumed at 88, the companion arm 89 having a roller 90 traveling in a cam groove 91 of cam 92 also fixed to the shaft 65, (Fig. 2).

The flat blank having been folded or bent

up to shape around the form, as thus described, it is desirable to press together the overlapping corner portions to secure their effective and adequate adhesion by reason of the glue, cement, or other adhesive applied to the flat blank before the bending operation. This pressing of these overlapped flaps and tabs is not accomplished by the folders or benders described above, but 10 rather by separate pressing instrumentalities.

To press the tab 35, coated on its inner surface with adhesive, against the outer face of the side flap 28, I provide an up-right lever 93, (Fig. 3), fulcrumed at 94, and shaped to form a presser 95 as shown in Fig. 9 and corresponding to the configuration of the tab 35, being tapered or beveled at its lower portion. This presser 20 95 is enabled to co-act with the tab 35 by reason of the space between the companion benders 70 and 71, thus giving access to the tab by the presser 95 for the performance of its function. Lever 93 is actuated by a toggle 96, 97, the link 97 being fulcrumed at 98 and the knuckle pin 99 of the toggle being connected by a link 100 to a lever 101 fulcrumed at 102 and equipped with a roller 103 traveling in a cam groove 104 in cam 30 105 on shaft 49. It is preferable to make the link 100 somewhat yielding to compensate for differences in the thickness of the pasteboard and it may be provided with any one of the usual spring constructions for 35 this purpose.

It is also desirable or necessary to press the glue-coated end flap 29 against the outer face of the inner flap 34 which it overlies, and against the corresponding face of the form, and to bring about this result the mechanism is provided with another lever 40 106, (Fig. 4), fulcrumed at 107 and shaped at its lower end to constitute a presser 108 of the shape shown in Fig. 2, (which is 45 substantially the same shape as the presser 95), and corresponding in configuration to the tab 34, it being noted, as is illustrated in Fig. 7, that the bender 84 is beveled or cut away on the line 109 so that the presser 50 55 may perform its work without interference with such bender or folder. Presser 108 is actuated by a toggle 110, 111, the link portion 111 being fulcrumed on a stationary shaft 112, the toggle being operated by a link 113, preferably some kind of a spring yielding link, pivoted at its lower end to a lever 114 hinged or fulcrumed at 115 and actuated by a roller 116 located in a cam groove 117 of cam 64 on shaft 65.

60 The parts are so shaped, arranged, and interconnected, that the folding operation is completed, whereupon the two pressers come into action and secure a very firm and uniform pressure on the overlapped surfaces 65 of the parts 28 and 35 and 29 and 34 to cause

their complete adhesion by reason of the glue previously applied to their surfaces. By the employment of toggles, these pressers can be made adequate for all purposes, it being understood that the blank folders 70 or benders are so shaped, as illustrated, that when they are rocked up toward the form, they do not overlap, the outer surface of flap 28 covered by the tab 35, nor the outer surface of flap 29 beneath which the tab 75 34 is positioned. Or, stated somewhat differently, these folders or benders are properly recessed to permit the pressers to reach the work and fulfil their functions without interference or conflict with the benders or 80 folders, and vice versa.

The box having been thus completed, it is discharged or stripped from the four forms simultaneously by reason of an ejecting mechanism associated with each. Each of 85 such devices comprises a right-angle stripper 118 engaging the two adjacent surfaces of the form and mounted on a reciprocatory rod 119 guided in bearings 120 and 121 and manipulated automatically by a link 122, 90 (Fig. 3), connected to a collar 123 on the rod and also connected to the rock lever 46. Ordinarily this stripper or discharge device is elevated to permit the folding operation, and it then descends at the proper 95 time to discharge the box.

The appliance may be driven or operated by any approved means, but in the device illustrated this is brought about by a pinion 124 on a drive-shaft 125, (Fig. 3), the pinion 100 meshing with the teeth of the large gear 53 on shaft 49 and, of course, the rotation of this shaft is carried to the shaft 65 through the co-operating bevel gears 67 and 66. 105

It is desirable in an apparatus of this kind to make it adjustable so that it can readily manufacture boxes of different sizes, and this part of the invention is shown diagrammatically in Fig. 8, wherein the four 110 forms and their operating mechanisms have been given the general reference characters A, B, C, and D.

The mechanisms A and B, and C and D, are adjustable toward and from one another 115 by means of shafts 126, 126, provided with operating handles 127, 127, and having screw-threaded connections 128 with the four devices, and in order to permit the gears 124 to remain in operative association 120 with their shafts 125, they remain slidably thereon, the shafts being equipped with keyways 129 in the usual way, which have sliding connections with the gears, the latter being compelled to travel with the four 125 mechanisms by reason of the yoke construction 130 shown associated therewith.

These two shafts 125, 125, are driven by means of co-acting bevel gears 131, 132, the gears 132 being slidably mounted on a drive 130

shaft 133 provided with a suitable keyway 134 co-acting with the gears.

The devices A and B and C and D are movable toward and from one another by 5 reason of the shafts 135, 135, having threaded connections 136 with the supports 137, 137, for the mechanisms A, B, C, and D, and on which supports said mechanisms are 10 slideable, as indicated above, by manipulation of the handle 127. These two shafts 135, 135, are connected together by a sprocket chain 138 and associated sprocket wheels 139 and 140. Any suitable means 15 may be employed for turning any one of these shafts 135, whereupon, of course, the other shaft will be rotated in like manner and corresponding amounts.

While I have herein described with some 20 degree of particularity one desirable embodiment of the invention, it is to be understood that it is not limited and restricted to the precise and exact details of construction because these may be varied within wide limits without departure from the 25 substance of the invention and without the sacrifice of any of its substantial benefits and advantages.

For example, it is not absolutely necessary under all circumstances that the tab 34 30 shall be preliminarily bent up and consequently, this portion of the mechanism may, in some instances be omitted. It will furthermore be observed that either one of the tabs 34 or 35 may be omitted and a box of 35 satisfactory character produced, though possibly not one quite as strong as where both tabs are used.

I claim:

1. In a box-making machine of the character described, the combination of a corner form, means to bend over a tab on a flap of the box blank adapted to constitute one of the walls of the box, means to bend toward the form such flap and a tab on 40 an adjacent flap adapted to form another wall of the box, means to bend said latter flap and its tab toward the form, whereby one flap and its tab will be bent to the form and around a corner thereof and the other flap and its tab will be bent to the form and around the same corner and overlap said inner flap and tab, and means to press said overlapped corner portions to cause 45 their adherence together, substantially as described.

2. In a box-making machine of the character described, the combination of a corner form, means to bend over a tab on a flap of the box blank adapted to constitute one of the walls of the box, means to bend toward the form said flap and a tab on an adjacent flap adapted to form another wall of the box, means to bend said latter flap and its tab 50 toward the form, whereby one flap and its tab will be bent to the form and around a corner thereof, and the other flap and its tab will be bent to the form and around the same corner and overlap said inner flap and tab, the tab of said outer flap during the folding operation being guided to the outside of the other flap by the bent tab of the latter, substantially as described.

its tab will be bent to the form and around a corner thereof and the other flap and its tab will be bent to the form and around the same corner and overlap said inner flap and tab, the tab of said outer flap during the folding operation being guided to the outside of the other flap by the bent tab of the latter, substantially as described.

3. In a box-making machine of the character described, the combination of a corner form, means to bend over a tab on a flap of the box blank adapted to constitute one of the walls of the box, means to bend toward the form said flap and a tab on an adjacent flap adapted to form another wall of the box, means to bend said latter flap and its tab toward the form, whereby one flap and its tab will be bent to the form and around a corner thereof and the other flap and its tab will be bent to the form and around the same corner and overlap said inner flap and tab, the tab of said outer flap during the folding operation being guided to the outside of the other flap by the bent tab of the latter, and means to press said overlapped corner portions to cause their adherence together, substantially as described.

4. In a box-making machine of the character described, the combination of a corner form, means to bend over a tab on a flap of the box blank adapted to constitute one of the walls of the box, means to substantially-simultaneously bend toward the form said flap and a tab on an adjacent flap adapted to form another wall of the box, means to bend said latter flap and its tab toward the form during the bending operation of the other flap, whereby one flap and its tab will be bent to the form and around a corner thereof, and the other flap and its tab will be bent to the form and around the same corner and overlap said inner flap and tab, the tab of said outer flap during the folding operation being guided to the outside of the other flap by the bent tab of the latter, substantially as described.

5. In a box-making machine of the character described, the combination of a corner form, means to bend over a tab on a flap of the box blank adapted to constitute one of the walls of the box, means to substantially-simultaneously bend toward the form said flap and a tab on an adjacent flap adapted to form another wall of the box, means to bend said latter flap and its tab toward the form during the bending operation of the other flap, whereby one flap and its tab will be bent to the form and around a corner thereof, and the other flap and its tab will be bent to the form and around the same corner and overlap said inner flap and tab, the tab of said outer flap during the folding operation being guided to the outside of the other flap by the bent tab of the latter, substantially as described.

6. In a box-making machine of the character described, the combination of a corner form, means to bend over a tab on a flap of the box blank adapted to constitute one of the walls of the box, means to bend toward the form said flap and a tab on an adjacent flap adapted to form another wall of the box, means to bend said latter flap and its tab toward the form, whereby one flap and its tab will be bent to the form and around a corner thereof, and the other flap and its tab will be bent to the form and around the same corner and overlap said inner flap and tab, the tab of said outer flap during the folding operation being guided to the outside of the other flap by the bent tab of the latter, substantially as described.

latter, and means to press said overlapped corner portions to cause their adherence together, substantially as described.

6. In a box-making machine of the character described, the combination of a corner form, a folder to bend over a tab on a flap of the box blank adapted to constitute one of the walls of said box, means to operate said folder, folding means to bend toward the form said flap and a tab on an adjacent flap adapted to form another wall of the box, means to actuate said folding means, folding means to bend said latter flap and its tab toward the form, and means to operate said latter folding means, whereby one flap and its tab will be bent to the form and around a corner thereof and the other flap and its tab will be bent to the form and around the same corner and overlap said inner flap and tab, hinged pressers to press said overlapped corner portions to cause their adherence together, and toggle means to operate said pressers, substantially as described.

7. In a box-making machine of the character described, the combination of a corner form, means to bend over a tab on a flap of a box blank adapted to constitute one of the walls of the box, means to bend toward the form said flap and a tab on an adjacent flap of the blank adapted to form another wall of the box, means to bend said latter flap and its tab toward the form substantially-simultaneously with the action of said first flap bending means, whereby one flap and its tab will be bent to the form and around a corner thereof and the other flap and its tab will be bent to the form and around the same corner and overlap said inner flap and tab, said bending means being shaped to avoid overlying either of said tabs, and means engaging the outer tab and engaging the outer flap over the inner tab and adapted to press said tab and flap together to cause their adhesion, substantially as described.

8. In a box-making machine of the character described, the combination of a corner form, means to bend over a tab on a flap of a box blank adapted to constitute one of the walls of the box, means to bend toward the form said flap and a tab on an adjacent flap of the blank adapted to form another wall of the box, means to bend said latter flap and its tab toward the form substantially-simultaneously with the action of said first flap bending means, whereby one flap and its tab will be bent to the form and around a corner thereof and the other flap and its tab will be bent to the form and around the same corner and overlap said inner flap and tab, said bending means being shaped to avoid overlying either of said tabs, and means adapted to engage the outer tab and

engage the outer flap over the inner tab to press said tabs and flaps together to cause their adhesion while the bending means still holds the bent blank to the form, substantially as described.

9. In a box-making machine of the character described, the combination of a corner form, means to bend over a tab on a flap of a box blank adapted to constitute one of the walls of the box, a hinged folder to bend toward the form said flap and a tab on an adjacent flap of the blank adapted to form another wall of the box, a hinged folder to bend said latter flap and its tab toward the form substantially-simultaneously with the action of said first flap folding means, means to operate said folding means, whereby one flap and its tab will be bent to the form and around a corner thereof, and the other flap and its tab will be bent to the form and around the same corner and overlap said inner flap and tab, said folding means being shaped to avoid overlying either of said tabs, and toggle-operated pressing means to engage the outer tab and the outer flap over the inner tab and adapt while the folding means still holds the bent blank to the form to press said tabs and flaps together to cause their adhesion, substantially as described.

10. In a box-making machine of the character described, the combination of a corner form immovable during the entire box forming and discharging operations, means to bend toward such form a flap of a box blank adapted to constitute one of the walls of the box and a tab on an adjacent flap adapted to form another wall of the box, means to bend said latter flap toward the form, whereby said flap and tab will be bent around the corner of the form and such tab and the other flap will overlap and adhere, and means to discharge the box from the form, substantially as described.

11. In a box-making machine of the character described, the combination of a corner form immovable during the entire box forming and discharging operations, means to bend toward such form a flap of a box blank adapted to constitute one of the walls of the box and a tab on an adjacent flap adapted to form another wall of the box, means to bend said latter flap toward the form, whereby said flap and tab will be bent around the corner of the form and such tab and the other flap will overlap, means to press said overlapped corner portions to cause their adherence together by reason of applied adhesive, and means to discharge the box from the form, substantially as described.

12. In a box-making machine of the character described, the combination of a corner form, means to bend toward the form a

flap of a box blank adapted to constitute one of the walls of the box and an associated tab and a tab on an adjacent flap adapted to form another wall of the box, and means to bend said latter flap and its tab toward the form, whereby one flap and its tab will be bent to the form and around the corner thereof and the other flap and its tab will be bent to the form and around the same corner and overlap the inner flap and tab, substantially as described.

13. In a box-making machine of the character described, the combination of a corner form, means to bend toward the form a flap of a box blank adapted to constitute one of the walls of the box and an associated tab and a tab on an adjacent flap adapted to form another wall of the box, means to bend said latter flap and its tab toward the form, whereby one flap and its tab will be bent to the form and around the corner thereof and the other flap and its tab will be bent to the form and around the same corner and overlap the inner flap and tab, and means to press said overlapped corner portions to cause their adherence together, substantially as described.

14. In a box-making machine of the character described, the combination of a stationary corner form and a rigid mounting therefor, means to bend toward the form a flap of a body blank adapted to constitute one of the walls of the box and a tab on an adjacent flap adapted to form another wall of the box, means to bend said latter flap and its tab toward the form whereby said flap and tab will be bent around the corner of the form and such tab and the other flap will overlap, and means mounted on the rigid mounting of the corner form adapted to press said overlapped corner portions to cause their adherence together, substantially as described.

15. In a box-making machine of the character described, the combination of a plurality of stationary corner forms each immovable during the entire box forming and discharging operations, means to bend a box blank about said forms to provide a box, and means to discharge the box from said forms, substantially as described.

16. In a box-making machine of the character described, the combination of a corner form immovable during the entire box forming and discharging operations, means to bend toward a face of said form a flap of a box blank adapted to constitute one of the walls of the box, means to bend toward another face of said form another flap of said blank adapted to form another wall of said box, means to bend a tab on one of said flaps around the corner of said form and into overlapping and adhered relation with the other flap, and means to discharge the

box from the form, substantially as described.

17. In a box-making machine of the character described, the combination of a corner form, means to bend toward a face of said form a flap of a box blank adapted to constitute one of the walls of the box, means to bend toward another face of said form another flap of said blank adapted to form another wall of said box, and means to bend a tab on each of said flaps around a corner of said form and into overlapping and adhered relation with the companion flap, substantially as described.

18. In a box-making machine of the character described, the combination of four separated corner forms, each immovable during the entire blank-folding and discharging operations, and means to bend flaps and tabs of a box blank about said forms and into overlapped and adhered relation to form the walls of the box, and means to discharge the box from the forms, substantially as described.

19. In a box-making machine of the character described, the combination of four separated corner forms each immovable during the entire blank-folding and discharging operations, and complete and independent means to bend flaps and tabs of a box blank about each of said forms and into adhered and overlapped relation, said bent flaps and tabs constituting walls of the box, and means to discharge the box from the forms, substantially as described.

20. In a box-making machine of the character described, the combination of an immovable corner-form, and a rigid mounting therefor, means to bend toward the form a flap of a body-blank adapted to constitute one of the walls of the box, means to bend toward the form a tab on an adjacent flap adapted to constitute another wall of the box, means to bend toward the form said latter flap and said tab, and means mounted on the rigid mounting of the corner-form adapted to press the overlapped corner portions of the box to cause their adherence together, substantially as described.

21. In a box-making machine of the character described, the combination of a plurality of corner-forms, a rigid mounting for each of said forms, said mountings and forms being immovable during the blank-folding and box-discharging operations, a blank-folding mechanism for each of said forms mounted on the respective rigid mountings of such forms, and means to discharge the box from said forms, substantially as described.

22. In a box-making machine of the character described, the combination of a form, means to bend to said form flaps of a box blank to constitute the sides of the box,

means to fold a tab at each end of each flap toward the form and into overlapped relation with the adjacent flaps, means to press said overlapped flaps and tabs together to secure their adhesion, and means to discharge the box from the form, substantially as described.

23. In a box-making machine of the character described, the combination of a form immovable during the box forming and box-

discharging operations, means to bend to said form flaps of a box blank to constitute the sides of the box, means to fold a tab on each end of each flap toward the form and into overlapped relation with the adjacent flaps, means to press said overlapped flaps and tabs together to secure their adhesion, and means to discharge the box from the form, substantially as described. 15
